PAPER TEAR-OFF DEVICE FOR TYPING APPARATUS

Harold W. Paschke, Chicago, Ill., assignor to Teletype Corporation, Chicago, Ill., a corporation of Delaware

Application July 17, 1939, Serial No. 284,825

6 Claims. (Cl. 197—133)

This invention relates to type printing apparatus, such as typewriters and page printing telegraph apparatus, and particularly to paper tear-off blades for printing mechanisms of the kind mentioned.

An object of the invention is to provide for the severance of single or multiple pages a wide range of distances from the printing point.

Another object of the invention is to provide for the retention of a tear-off blade in a retracted or ineffective position, solely in consequence of movement of the blade to that position.

A further object of the invention is to provide for the guiding of transversely creased or otherwise bulging single or multiple page material supplied in continuous lengths underneath the paper tear-off blade.

The invention features adjustable rests for spring biased supporting arms for a paper tear-off blade which support the tear-off blade in any desired position relative to the printing position and which offer no hindrance to manual retraction of the paper tear-off blade to an ineffective position.

Briefly, the preferred embodiment of the invention contemplates the attachment, to the platen carriage of a typewriting or printing telegraph machine, of pivoted arms which carry at their foremost ends a paper tear-off blade extending longitudinally of the platen above the printing position. Adjustable stop screws co-operate with the arms which support the tear-off blade to determine and permit variation of the position of the tear-off blade relative to the printing position. A spring which is distended between a spring post on the platen carriage and a similar post on one of the arms which support the tear-off blade biases the blade supporting structure into operative position, as determined by the stop screws. When the tear-off blade is retracted to its ineffective position, the axis of the spring passes from one side to the other of the pivotal axis of the tear-off blade supporting arms, and thus, operating as an over-center device, retains the blade in the retracted position. The tear-off blade is provided with flexible spring fingers which extend inwardly and downwardly toward the printing position for guiding any bulging portion of single or multiple page strips beneath the tear-off blade. An example of such bulging portions of page material is the outward or protruding creases in zig-zag folded lengths of page material.

For a complete understanding of the invention, reference may be had to the following

detailed description to be interpreted in the light of the accompanying drawing in which:

Fig. 1 is a perspective view of the platen carriage of the typewriting or printing telegraph machine, including a paper tear-off blade structure in accordance with the invention;

Fig. 2 is an elevational view taken at the left-hand end of the platen carriage shown in Fig. 1; and

Fig. 3 is an elevational view of the tear-off blade structure and its mounting only, as viewed at the right-hand end of Fig. 1.

For convenience in illustrating the invention, it has been shown in the drawing applied to the platen carriage of a printing telegraph machine, such as that shown in Patent No. 1,904,164 granted April 18, 1933, to S. Morton et al. This patent discloses a page printing mechanism in which a cylindrical printing platen is rotatably supported in a cradle which is pivotally mounted upon portions of the frame of the printer. The frame may be rocked upon its pivot for upper and lower case printing, but there is no provision for longitudinal movement of the printing platen for character spacing. Instead, the type bars are arranged in a type basket carriage which is supported by rollers upon rails for movement parallel to the axis of the platen for character spacing and for return to beginning-of-line position. Such type printing mechanism is particularly adapted to the handling of single or multiple continuous page width paper, for the reasons that the portions of the paper between the supply rolls or pack and the platen carriage are not subjected to shifting movement laterally, as is the case when such paper supplies are used on type printing machines in which the platen carriage travels back and forth across the machine for spacing operations.

Referring now to the drawing, the reference numeral 11 designates spaced upper portions of the frame of a type printing apparatus. Frame portions 11 have mounted thereon opposed pilot screws 12 which engage and pivotally support a platen carriage or cradle indicated generally by the reference numeral 13 and comprising as principal elements the right and left-hand end plates 14 and 16, respectively, interconnected, for undergoing identical pivotal movement, by a connecting bar 17. Cradle end plates 14 and 16 are provided with bosses 18 and 19, respectively, which rotatably support platen shaft 21. Shaft 21 supports, between the end plates 14 and 16, a platen 22 which, in the particular embodiment of the invention disclosed, is pro-

vided with sprocket pins 23 for entering marginal apertures 24 in one or a plurality of continuous page width forms to impart paper advancing movement when platen 22 is rotated. Rotation may be imparted to platen 22 in clockwise direction, as viewed at the right-hand end of Fig. 1, by a line feed mechanism (not shown). A spring biased detent 27 co-operates with a ratchet 26 secured to one end of platen 22 to determine positive stop positions for platen 22 and to maintain the platen in those positions so that printing shall be accomplished in straight and accurately spaced lines.

Each of the end plates 14 and 16 has pivoted thereto by means of screws, such as 28 (Fig. 2), mounted below and behind platen shaft 21, arms 29 and 31, to the free ends of which is secured a paper tear-off blade 32 extending parallel to the platen shaft 21. Between the arm 29 and cradle end plate 14, there is secured to the plate 14 a bracket 33 which has a laterally extending ear 34 and which also supports the spring post 36. An abutment screw 37 threadedly engages the ear 34 and is provided with a head 38 in alignment with tear-off blade supporting arm 29, against which arm 29 may rest to determine operating position of tear-off blade 32. At its opposite end, screw 37 is provided with a slot 39 by means of which it may be rotated to vary the pivotal position of arm 29 relative to the platen shaft 21 and, therefore, to vary the elevational position of blade 32 with respect to the platen. Screw 39 is also provided with a lock nut 41. Arm 29 carries a spring post 42 and a tension spring 43 is distended between posts 36 and 42 to bias arm 29 into engagement with spherical head 38 of screw 37.

Arm 31, which is pivotally supported by cradle end plate 16, is provided with an upwardly extending arm 44 which terminates in a laterally bent portion 46, which is threadedly engaged by an abutment screw 47. End plate 16 has integral therewith a boss 48, the peripheral surface of which the inner end of screw 47 abuts when arm 31 is to hold blade 32 in operative position. By varying the adjusting of screw 47, the angular position of arm 31, relative to platen shaft 21, may be varied. A lock nut 49 is associated with screw 47 for locking the screw in any desired position of adjustment.

Although tear-off blade 32 is rigidly secured by screws to pivoted arms 29 and 31 so that regardless of whether the angle of arm 29 or 31 be changed, or whether blade 32 itself be lifted, the assembly comprising arms 29 and 31 and blade 32 will move as a unit. However, in order that blade 32 shall always be maintained in parallelism with shaft 21, it is desirable that when blade 32 is being used in paper tearing position, arm 29 shall abut the spherical head of screw 37 and the inner end of screw 47 shall abut the peripheral surface of boss 48. Furthermore, the screws 37 and 47 should be so adjusted relative to the ears 34 and 46 which they threadedly engage, that the free ends of arms 29 and 31 shall be at the same elevation and, therefore, that blade 32 shall be parallel to shaft 21.

Variation in the position of blade 32 is accomplished by varying the adjustment of the two screws 37 and 47 to change the angular positions of arms 29 and 31. Such variation is desirable because occasions arise for severing stationery, upon which message material has been printed, at varying distances from the printing line. For example, the stationery may be continuous strips

of printed forms having transverse weakening lines between each two forms. For certain purposes, the forms may be one length and for other purposes they may be of different lengths. Also, the amount of space devoted to printed headings may vary with different forms, thus varying the position for the printing of the first line of message material with respect to the upper edge of the form. One mode of operation, under which the tear-off blade may be employed, is that when a form, upon which message material is to be printed, has been advanced to bring the point at which the first line of printing is to appear into registry with the printing position, the upper edge of that form and, therefore, the transverse weakening line between it and the form which preceded it will be in registry with the upper edge of the blade 32. The form upon which the preceding message material was printed is thus in position to be severed and may be severed by the co-operation of the edge of blade 32 with the transverse weakening line, or by means of such weakening line without the actual co-operation of the blade 32, the blade merely serving as a reference line for the positioning of the form upon which the next material is to be printed. Thus, the tear-off blade 32 may serve as a convenient means for bringing a printed form into the proper position to receive the first line of message material, this being accomplished by bringing the transverse weakening line into registry with the upper edge of the tear-off blade, or the point of severance may be determined by the position of the tear-off blade when a form has been brought into position for the printing of the first line of message material. The difference is largely one of viewpoint rather than of operation when continuous forms having transverse weakening lines are used, but with continuous forms having no weakened severance lines or other indications of the tear-off points, a different situation exists. With stationery of the latter kind, the advancement of a form into position for the printing of the first line brings the point at which the preceding form should be severed into registry with the upper edge of the tear-off blade 32, if the tear-off blade has been correctly positioned in advance by adjusting screws 37 and 47 to fix the position of blade 32 at the desired distance from the printing line, and the form or assembly of forms upon which message material had previously been printed may be severed by drawing it against the edge of the tear-off blade without the necessity for transverse weakening lines.

For some purposes, such as the printing of message material on continuous lengths of blank paper, or upon continuous forms characterized by very narrow headings, it may be desirable to position the tear-off blade as close as possible to the printing position, in order to minimize the amount of blank paper between the upper edge and the first line of printed material, or to print the first line of message material relatively close to the heading. With the structure disclosed in the drawing, the pressure rollers 51 are the only elements in the structure which prevent bringing the lower edge of the tear-off blade down to the printing line. It is to be noted that arms 29 and 31 are provided with offsets so that the bosses 18 and 19, in which platen shaft 21 is journaled, shall not prevent the bringing of blade 32 as close to the printing line as pressure rollers 51 will permit.

Operating circumstances have been encountered under which it may be desirable to have the

blade 32 positioned for active co-operation with the stationery at considerable distances from the printing line. Such operating conditions are exemplified in the use of forms having relatively wide headings. It has also been found desirable to be able to move the tear-off blade quickly and easily to an ineffective position, in which position it shall remain until it is again to be rendered effective, such movement to ineffective position having the purpose of clearing the front portion of the platen carriage so that adjustments may be made or new forms fed into cradle 13. The double feature of wide range of effective positions of the tear-off blade and easy movement of the blade to an ineffective position where it shall remain has been accomplished by so locating spring post 36 with respect to the axis about which arms 29 and 31 rock, that spring 43 shall be disposed forwardly of the axis of rotation of arms 29 and 31 throughout the range of adjustment desired and arm 29 shall thus be biased in counterclockwise direction, as viewed in Fig. 3, into engagement with head 38 of screw 37 and arm 31 shall be biased clockwise, as viewed in Fig. 2, to maintain screw 47 in engagement with boss 48. Sufficient additional rearward movement of blade 32, to which corresponds clockwise movement of arm 29, as viewed in Figs. 1 and 3, is permitted, to cause spring 43 to move to the rear of the pivotal axis of arms 29 and 31. This results in an over-center condition and causes spring 43 to bias arm 29 in clockwise direction instead of counterclockwise. Movement of blade 32, after spring 43 has passed over center rearwardly, is limited by engagement of projection 44 of arm 31 with the top of the left-hand frame member 11 upon which end plate 16 is pivotally supported. Projection 44 engages the upper end of bracket 11 just soon enough after spring 43 has passed across the pivotal axis of arms 29 and 31, so that spring 43 will retain blade 32 in this ineffective or rest position. Further rearward movement of blade 32 would be of no advantage. When blade 32 is to be restored to effective or operative position, it need be moved forwardly only a sufficient distance to overcenter the spring 43 in the forward direction, whereupon the spring will rock arm 29 forwardly which will impart similar movement to arm 31 until both arms have been arrested by their stop screws 37 and 47.

Adjacent to the point at the foremost ends of pivoted arms 29 and 31 where tear-off blade 32 is secured, the arms have been provided with shoulder screws 52 upon and under the heads of which flexible paper guiding fingers 53 are mounted. Fingers 53 are made of very thin spring metal and the portions under the heads of screws 52 are twisted or otherwise deformed and the deformed parts are partially compressed so as to be held between the heads of screws 52 and the ends of arms 29 and 31 with sufficient friction that the fingers shall remain in any angular position in which they are adjusted relative to blade 32. Fingers 53 are bent inwardly so that they shall seek engagement with the paper. The purpose of fingers 53 is to guide the paper beneath tear-off blade 32. They are required principally, when blade 32 is employed at a considerable distance from the printing line to prevent the upper edge of a form or set of forms from which the preceding forms have been severed from escaping out from under the blade 32. They also have utility when stationery supplied in zig-zag folded form is employed in the printer. Such stationery presents alternate inward and outward folds, 75

or creases, and the outward folds may not advance properly to and pass under the blade 32 unless guided in advance by some means, such as the fingers 53.

Preferably, the fingers 53 are adjusted in such angular position, relative to and extending downwardly from blade 32, so that the inner surfaces at the free ends shall just fail to engage the paper as it passes from the printing position to the tear-off blade. Thus, the paper will not be dragged under the fingers in engagement therewith, and undesirable marking or smudging of carbon copies will be avoided. Any tendency of the paper to bulge outwardly and escape from beneath blade 32 will be corrected by flexible fingers 53. It will be apparent that since arms 29 and 31 are pivoted below and behind the axis of platen 22, the angles of fingers 53, relative to blade 32, in order to bring the ends of the fingers in close proximity to the surface of the paper will vary as the elevation of blade 32 relative to the printing line is varied. When the blade 32 is adjusted relatively close to the printing position, the pressure rollers 51 will be adequate in preventing the paper from escaping from under the blade 32 and fingers 53 may be swung upwardly until they extend along and rest against the outer surface of blade 32, where they will be out of the way.

Although a specific embodiment of the invention has been shown and described herein, it will be understood that the invention is not limited to the specific details set forth, but is capable of modification and rearrangement without departing from the spirit of the invention and within the scope of the appended claims.

What is claimed is:

1. In a typing apparatus having a cylindrical platen for supporting paper in type receiving position, a paper tear-off blade extending longitudinally of said platen, pivotally mounted means for supporting said blade, adjustable means for determining several effective positions of said blade longitudinally of the paper and for maintaining said blade while in said several positions in parallelism but out of engagement with said platen, and yieldable means for urging said blade into the several effective positions.

2. In a typing apparatus having a cylindrical platen for supporting paper in type receiving position, a paper tear-off blade extending longitudinally of said platen, a pair of arms pivoted below and behind the axis of said platen and supporting at their free ends said blade, adjustable means co-operating with said arms for determining several effective positions of said blade longitudinally of the paper and for maintaining said blade while in said several positions in parallelism but out of engagement with said platen, and yieldable means for urging said arms to the several positions determined by said adjustable means.

3. In a typing apparatus, a platen carriage, a platen rotatably supported in said carriage, a tear-off blade extending longitudinally of said platen above the printing line, an arm at each end of said carriage pivoted thereto below and behind the axis of said platen and supporting at its free end said tear-off blade, spring means for biasing said blade toward the printing line, and an adjustable abutment screw co-operating with each arm to hold said blade at any desired distance from the printing line and in parallelism with the axis of said platen.

4. In a typing apparatus, a platen carriage, a

platen rotatably supported in said carriage, a tear-off blade extending longitudinally of said platen above the printing line, an arm at each end of the carriage pivoted thereto below and behind the axis of the platen and supporting at its free end one end of said tear-off blade, a spring post carried by said carriage immediate below the pivotal mounting of one of said arms, a spring post carried by the arm below which said first mentioned spring post is mounted, a tension spring distended between said posts and movable across the pivotal axis of said arms upon the shifting of said blade a predetermined distance from the printing line, and means co-operating with said arms for holding said blade at any point within said predetermined distance in opposition to said spring.

5. In a typing apparatus, a platen carriage, a platen supported in said carriage, a paper tear-off blade extending longitudinally of said platen above the printing line, an arm at each end of the carriage pivoted thereto below and behind the printing line and supporting at its free end

one end of said tear-off blade, means co-operating with said arms for determining effective positions of said blade, and a spring for biasing one of said arms to present said blade in effective positions, said spring being operable as an over center to hold said blade in an ineffective position.

6. In a typing apparatus, a platen carriage, a cylindrical platen rotatably supported in said carriage, a tear-off blade extending longitudinally of said carriage, an arm pivoted at each end of the carriage below and behind the axis of said platen and supporting at its outer end one end of said blade, means co-operating with said arms for determining pivotal positions of said arms and thus effective positions of said blade, and paper guiding fingers carried by said blade, said fingers being adjustable upon said blade according to the position of the blade to be normally out of contact with paper approaching said blade yet to prevent bulging of said paper below and forwardly of said blade.

HAROLD W. PASCHKE.
